UNITED STATES PATENT OFFICE.

WILLIAM A. McCURDY, OF VIRGINIA, MINNESOTA.

SAFETY CAR COUPLER.

Application filed March 28, 1927. Serial No. 178,886.

This invention relates to an improved railroad draft appliance and more particularly to a safety draft appliance in which injury to the operator is prevented through accidental introduction of parts of his body between the parts of the mechanism.

Draft appliances now in use usually comprise a coupler element having a coupler head and shank which is connected in operative relation with the car sill for imparting a pull or a thrust thereto through the instrumentality of the yielding connection known as the draft gear. The draft gear is connected to the inner end of the coupler shank by means of a suitable yoke. The outer end of the car sill is provided with a plate with an opening therein which closely surrounds the coupler shank, which plate is in abutment with the end of the sill so as to form a striking plate. The coupler shank near the coupler head is provided with a coupler horn which is in spaced relation with the striking plate when the parts are in unloaded position but which is adapted to contact the striking plate to impart a thrust directly thereto and to the car sill when the shank through the maximum yielding of the draft gear is caused to move an abnormal extent, as under excessive compression. The movement allowed for the normal operation of the draft gear, or in other words, the space provided between the coupler horn on the coupler shank and the striking plate, is usually about three or more inches.

It has been found in practice that a great number of accidents which result in serious injury to the operator of the car coupler have occurred by the accidental introduction of parts of the body of the operator between the coupler horn and the striking plate. This is readily apparent when it is understood that these parts are on the top of the coupler in such a position and presenting an opening of such a size that the operator in standing on the coupler can place his foot therein, or if reaching over the coupler when standing on the ground, is apt to accidentally place his hand or arm therebetween. Frequently the thrust which causes an engagement between the coupler horn and the striking plate is imparted through a number of cars from a comparatively remote source, and the operator is apt to be caught unaware of the danger and be severely injured.

To this end, the primary object of my in-

vention is to provide a coupler embodying all the features of the customary type, having a coupler head and shank connected through the usual draft gear construction to the car sill, provided with a coupler horn and a striking plate which are so disposed relative to the car sill that accidental introduction of parts of the body of the operator is prevented.

This and other objects are accomplished by means of the arrangement disclosed on the accompanying sheet of drawings, in which—

Figure 1 is a plan view of a draft appliance constructed in accordance with my invention, and

Figure 2 is a side elevation partly in cross-section disclosing the relationship of parts when in an unloaded condition.

The various novel features of the invention will be apparent from the following description and drawings and will be particularly pointed out in the appended claims.

Referring to the drawing, it will be noted that my invention is disclosed as applied to a draft appliance of the customary type which comprises a coupler element 10 having a head 11 and a shank 12. The shank of the coupler is introduced between the car sill beams 13 and is connected thereto through the instrumentality of a draft gear, not shown, and a yoke 14 and key 15. The outer end of the sill is provided with a collar 16 which surrounds the coupler shank in a manner to provide a clearance 17 on the sides thereof for permitting lateral movements of the coupler relative to the sill but with slight clearance as shown at 18 above the coupler shank. The coupler shank normally rests as at 18' on the collar, but it is free to move slightly both upwardly and laterally. Mounted between the sills 13 and attached to the web portions thereof is the striking plate 19 having a contacting surface 20 and side web portions 21 which are attached to the webs of the sill by suitable rivets 22. The coupler shank is provided on its upper surface with an enlargement in the form of a shoulder 23 which is otherwise known as the coupler horn. This horn is substantially of the same type provided on coupler shanks of the customary type but in the embodiment shown, is substantially 5½ inches further removed from the coupler head, thereby presenting an elongated enlargement as shown. In addition to

the outer ring 16, the opening in the car sill 18

is closed by portions of the car structure designated 24 bent over at the upper end, as shown in Figure 2 as at 25, and adapted to overlie a sheet of material 26 positioned 5 across the upper ends of the sill beams 13.

The parts as shown in Figures 1 and 2 are in unloaded position, or in other words, when there is no load on the draft gear, as in the act of imparting a thrust or pull to the sill 10 from the coupler, and the striking plate and the coupler horn are so disposed relative to the sill that the gap formed between the horn and the striking plate is housed within the parts of the sill. The movement usually provided 15 between the horn and striking plate, through which the coupler is permitted to move before it imparts the thrust through the striking plate directly to the sill for effecting a yielding application of force 20 through the instrumentality of the draft gear, is likewise provided in applicant's invention, but the parts are removed a distance inwardly so as to be housed within the sill.

In operation, it can be readily seen that I 25 have provided a draft appliance which embodies all the advantages of the draft appliance of the customary type but which in addition provides a striking plate and a coupler horn so disposed relative to the car sill that 30 it is impossible for the operator to accidentally introduce parts of his body whereby he is in danger of injury. It is to be understood that the essential features of this invention reside in the location of the coupler horn and 35 the striking plate relative to the car sill and that these features may be applied to any type

of coupler where the danger referred to is present.

I claim:

1. In a railway draft appliance, a coupler shank having a coupler horn thereon, a car sill, a striking plate mounted on and housed within said sill, said coupler shank extending into said sill an extent to house said coupler horn therein when in an unloaded position. 40

2. In a railway draft appliance, a coupler shank having a coupler horn thereon, a car sill, said shank extending into said sill an extent to house said coupler horn therein when in an unloaded position, and a striking 50 plate mounted on and housed within said sill and spaced from said coupler horn.

3. A railway draft appliance comprising a coupler shank having a coupler horn, a car sill and a striking plate, said coupler horn 55 and striking plate being spaced when in an unloaded position and completely housed within said sill.

4. A railway draft appliance comprising a coupler shank having a coupler horn, and a 60 striking plate, said parts being spaced from each other when said appliance is in an unloaded position but being adapted to contact when under abnormal compression, said parts being completely housed whereby accidental introduction of parts of the body of the operator between said coupler horn and striking plate is prevented. 65

Signed at Virginia, Minnesota, this 12th day of March, 1927.

WILLIAM A. McCURDY.
